UNITED STATES PATENT OFFICE.

JAMES B. SEXTON, OF PELLA, IOWA.

WAGON-BRAKE LEVER.

SPECIFICATION forming part of Letters Patent No. 227,847, dated May 18, 1880.

Application filed November 20, 1879.

To all whom it may concern:

Be it known that I, JAMES B. SEXTON, of Pella, in the county of Marion and State of Iowa, have invented certain new and useful 5 Improvements in Wagon-Locks and Brake-Levers; and I do hereby declare that the following is a full, clear, and exact description of the construction and operation of the same, reference being had to the annexed drawings, 10 making a part of this specification, and to the letters and figures of reference marked thereon.

Figure 1 of the drawings is a side elevation of my wagon-lock and brake-lever. Fig. 2 is an end view of the same, and Figs. 3 and 4 15 are detail views.

This invention relates to vehicle-brakes; and it consists in the improvements in the construction of the same, hereinafter fully described, and particularly pointed out in the 20 claims.

In the accompanying drawings, A designates the double sector-rack, which is composed of the two rack-bars *a a*, having teeth in their upper edges, and secured side by side, so as 25 to leave an intermediate way for the travel of the lower end of a brake-lever, B. This brake-lever B is pivoted between the cross-bars C C' of the sector-rack, and extends between the two rack-bars, so that all lateral play or wabbling upon its pivot will be effectively prevented. The bar C' extends only sufficiently 30 far to form a bearing for the pivot of the brake-lever, while the bar C extends from arm *a* to arm *a* upon its side of the sector-rack.

35 D designates the latch-lever, which is pivoted at the upper end of the lever-bar B, and E designates the gravity pawl or latch, which is pivoted at the lower end of the said lever-bar, so as to engage with the double lines of 40 teeth of the sector-rack, the said pawl and latch-lever being connected by means of a latch-rod, F.

The devices for connecting the brake-rod G with the brake-lever B are constructed as follows: H refers to a sliding sleeve, which is arranged upon the brake-lever; and I, a thumb-screw for securing the sleeve at any desired point upon the same.

K designates a plate formed with a sleeve, L, 45 which screws upon the end of the brake-rod G, and, as herein illustrated, this plate is con-

nected with the sleeve H by means of a pivot, M, which passes through an extended portion of the said sleeve.

In order to prevent the pivot from working 55 out of its bearing in the sleeve, I pass a pin, N, through its end, whereby the parts will be properly held together during use.

In order to adjust the sleeve H upon the brake-lever so as to increase or decrease the 60 leverage, it will simply be necessary to loosen it upon the lever by partially unscrewing the thumb-screw, and then slip it toward or away from the fulcral bearing of the brake-lever, after which the thumb-screw will be again 65 tightened up.

In order to tighten up the brake-rod so as to take up all unnecessary slack, I remove the pin N from the pivot of the plate K, and then disconnect this plate from the sleeve upon the 70 brake-lever, so that it may be turned round sufficiently to screw up its sleeve upon the brake-rod, after which it is reconnected with the sleeve, as before.

As herein shown, the sector-rack is connected with the side of a wagon by a bracket, and, when desired, this may be transferred from one side to the other of the wagon. In order to accomplish this it will be necessary to reverse the brake-lever, and hence I extend 75 80 the bar C' only part way between the ends of the rack-bars, so that a space will be left for the removal of the same after its pivot has been removed from the frame of the sector-racks.

The advantages of my adjustable connection between the brake-lever and brake-rod will be evident upon comparison with the old way, which usually consists in forming the brake-lever with a series of holes, through 90 which the pivot of the connecting-yoke is passed. Under my improvement I am not limited to determinate distances of adjustment, but may adjust the sleeve to any desired degree, whether great or small.

Having thus described my invention, what I claim, and desire to secure by Letters Patent, is—

1. In a wagon-brake, the double sector-rack A, having downwardly-curved rack-bars *a a*, 100 with teeth in their upper edges, and the brake-lever B, extended between the two bars of the

said rack and having a gravity-pawl arranged to engage with the same, substantially as herein shown and set forth.

2. The brake-lever B, in combination with the double sector-rack A, having the arms C C', which form a space for the removal of the brake-lever, whereby it may be reversed when the brake is changed from one side of the wagon to the other, substantially as shown and set forth.

3. The plate K, having a sleeve, L, adapted to be screwed upon the brake-rod, and a pivot, M, detachably connected with a sleeve, H, upon the brake-rod, substantially as shown and set forth.

4. The sleeve H, arranged to slide upon the brake-lever and provided with a thumb-screw for securing it in position thereon, in combination with the brake-rod and the plate K, having sleeve L, pivoted to said sleeve H, substantially as shown and set forth. 20

In testimony that I claim the above I have hereunto subscribed my name in the presence of two witnesses.

JAMES B. SEXTON.
